DOOR BURGLAR ALARM

Joseph J. Malespina, Waldwick, N.J., assignor to American District Telegraph Company, Jersey City, N.J., a corporation of New Jersey

Filed May 10, 1965, Ser. No. 85,193

Term of patent 14 years

(Cl. D72—1)

FIG.3.

FIG.1.

FIG.2.

FIG.5.

FIG.4.

FIG. 6

FIG. 1 is a front elevational view of a door burglar alarm embodying my design;

FIG. 2 is an elevational view taken from the left side thereof;

FIG. 3 is an elevational view taken from the right side thereof;

FIG. 4 is a top plan view thereof;

FIG. 5 is a bottom plan view thereof; and

FIG. 6 is another front elevational view thereof on a reduced scale. The broken line representation of a door and its associated frame in FIG. 6 is for purposes of illustration only.

I claim:

The ornamental design for a door burglar alarm, as shown and described.
